UNITED STATES PATENT OFFICE.

LEE H. WILLIAMS, OF INDIANAPOLIS, INDIANA, ASSIGNOR OF ONE-HALF
TO THE MCELWAINE-RICHARDS COMPANY, OF SAME PLACE.

WATER-HEATER.

SPECIFICATION forming part of Letters Patent No. 597,927, dated January 25, 1898.

Application filed June 16, 1897. Serial No. 641,050. (No model.)

To all whom it may concern:

Be it known that I, LEE H. WILLIAMS, of Indianapolis, county of Marion, and State of Indiana, have invented a certain new and useful Water-Heater; and I do hereby declare that the following is a full, clear, and exact description thereof, reference being had to the accompanying drawings, in which like numerals refer to like parts.

10 My invention relates to water-heaters employed chiefly in houses for domestic use.

The object of the invention is to secure a heater that is simple of construction, strong and durable, economical, and more efficient than similar devices heretofore made.

One feature of the invention consists in making the water-chamber of the heater of one piece by casting the same, so as to bring about increased strength and diminution in 20 size and an increase in the comparative heating efficiency.

Another feature is to render it possible to remove incrustations from the inner surface of the water-chamber without removing the 25 heater from the boiler and to otherwise make such operation simple and easy.

Another feature is to construct the fuel-outlet so that back drafts will not blow out the gas or fire.

30 There are other features of invention which will be understood from the description and claims following and the accompanying drawings.

In the drawings, Figure 1 is a vertical section of the hot-water boiler and heater with the necessary pipes and appurtenances thereto attached. Fig. 2 is a section on the line 2 2 of Fig. 1. Fig. 3 is a bottom view of the heater on the line 3 3 of Fig. 1.

40 In detail, 1 is a suitable stand for the hot-water tank or boiler 2. 3 is a suitable inlet-pipe for the cold water, while 4 is an outlet-pipe for the hot water from said tank or boiler. 5 is an outlet-pipe from the tank or boiler leading to the heater, and 6 is a pipe leading from the heater to the boiler.

45 The heater consists of a hot-water chamber 7, with an opening at its upper end which is closed by the disk or plate 8. The water-chamber 7 of the heater is preferably cast in substantially the form shown. In forming or

casting the same a tapering extension 13 extends centrally from the lower end partially through the chamber forming the heating-chamber 9. At the lower end of this heating-chamber the gas-burner 10 or any suitable burner is located, so that the flame therefrom will strike the water-chamber at its lower end and extend up almost to the chimney or hot-air pipe 12, which leads from the upper end 60 of the extension 13, as shown. A gas-pipe 11 supplies the burner 10. The burner is prevented from extending so far up that the flames therefrom will not come in contact with the lower part of the water-chamber by 65 means of the arms 24, secured to a collar that is fastened on the gas-pipe just below the burner. The length of the arms is such that they come in contact with the lower part of the chamber and prevent the burner from 70 being placed too high.

The extension 13, that forms the heating-chamber 9, is at its lower end some distance from the outer wall of the chamber 7. At least sufficient room is thereby provided for the 75 entrance of the pipe 5, leading from the boiler, and for the holes closed by the nuts or plugs 14. Preferably three of these openings are provided besides the one through which the pipe 3 enters.

80 The outside wall of the water-chamber 7 extends vertically for some distance and then is contracted, so that the volume of water surrounding the upper part of the inner wall 13 is greater than that which surrounds the 85 lower part or base, because at the upper part the heat is greater than it is below. By this construction, therefore, the volume of water is in proportion to the extent of heat that is applied to it. Around the upper part of the 90 opening of the water-chamber 7 I provide an annular horizontal flange 15, to which the closing-plate 8 is bolted securely. This plate has a central opening in it for the pipe 12 and a vertical annular collar 16 of greater diameter than the pipe 12. Between this collar and the pipe suitable packing, asbestos wick being preferable, is placed. To hold said packing in place, a second or upper plate 17 is bolted to the lower plate 8. Said upper plate 100 has a downwardly-extending annular collar 20 large enough to pass over the annular col-

lar 16 on the lower plate, and an annular recess in said upper plate adjacent to said collar is made to snugly receive the upper end of the collar 16 on the lower plate 8. By screwing down said plate tightly the packing is greatly compressed around the pipe 12, so as to prevent any escape of the heated water. 5
10 Detachably secured about the upper plate 17 there is a conical or tapering pipe 21, leading to the outlet-pipe 22 for the purpose of conveying the hot air from the burner below that passes through the pipe 12. The pipe 12 extends into the tapering outlet-pipe 21 about half-way. The plate 17 is provided 15 with a series of holes 23, through which air can pass into the pipe 21 and outlet-pipe 22; but the main function of said opening 23 is to serve as an outlet for any back draft that may be caused by any means down through 20 the pipe 22 and conical pipe 21. Such back draft, by escape through the openings 23, it is obvious will not blow out the fire below in the burner 10. This is of value because a sudden back draft is liable to blow out the 25 flame and leave the gas escaping very rapidly, whereby an explosion may result.

In this description it will be observed that the incrustations that may be formed on the inner surface of the water-chamber can be 30 removed without removing said water-chamber or separating it from the boiler. This is done by removing the plate 8 after loosening the bolts that secure it to the water-chamber. Then through the opening in the upper end 35 of the water-chamber a chisel or other implement can be introduced for loosening the incrustations. The particles of material thus loosened are removed through any of the holes in the bottom of the water-chamber after re- 40 moving the plugs 14, that close them. In fact the hand can be introduced in the opening at the upper end of the water-chamber. This mode of cleaning the water-chamber is a very simple and effective one, without disturbing 45 the water-tight joints of the connection between the water-chamber and the boiler.

What I claim as my invention, and desire to secure by Letters Patent, is—

1. A water-heating apparatus including a water-chamber contracted and open at its upper end with an annular flange surrounding such opening and with the central portion of its bottom extending upward and tapering to form a heating-chamber and holes in the bottom of the water-chamber, a plate for closing the opening at the upper end bolted to said annular flange, and detachable plugs for closing the holes in the lower end of such water-chamber, substantially as set forth. 50

2. In a water-heating apparatus, the combination with a suitable burner, of a water-chamber with a central upward extension from the bottom surrounding said burner, an outlet-pipe leading upward from the upper end of said extension for the escape of the 60 gases from the burner, a pair of plates for closing the upper opening in said water-chamber and surrounding said pipe, the lower of said plates being secured by bolts to said water-chamber and having an annular collar on 65 its upper side surrounding said outlet-pipe, packing filled in said annular collar around said pipe, and the upper one of said plates being secured to the lower one by bolts and having a downwardly-extending annular 70 flange that snugly surrounds the annular flange from the plate below, substantially as set forth.

3. In a water-heating apparatus, the combination with a burner, of a water-chamber 80 with a passage centrally upward through the same for the escape of gases from said burner, a plate surrounding said outlet-pipe provided with one or more apertures therein, and a conical pipe secured to said plate and extending 85 upward above said outlet-pipe to the outlet, whereby any back draft will escape through the apertures in said plate, substantially as set forth.

In witness whereof I have hereunto set my 90 hand this 25th day of May, 1897.

LEE H. WILLIAMS.
